UNITED STATES PATENT OFFICE.

FRANCIS M. BRINCKERHOFF, OF ENGLEWOOD, NEW JERSEY, ASSIGNOR TO LEWIS B. STILLWELL, OF LAKEWOOD, NEW JERSEY, AND HENRY S. PUTNAM, OF NEW YORK, N. Y.

RAILWAY-CAR CONSTRUCTION.

1,231,235.

Specification of Letters Patent. Patented June 26, 1917.

Application filed August 20, 1914. Serial No. 857,619.

To all whom it may concern:

Be it known that I, FRANCIS M. BRINCKERHOFF, a citizen of the United States, residing at Englewood, in the county of Bergen and State of New Jersey, have invented certain new and useful Improvements in Railway-Car Construction; of which the following is a specification.

My invention relates to new and useful improvements in railway car construction, the primary object being to construct a body end structure for a car, which will resist collision impacts.

A further object is to provide a body end structure which will tie the side walls of the car together at or about the roof line to thereby prevent separation or spreading of the walls and resulting in telescoping of cars.

20 A further object is to so brace the body end structures that movement of the same inward lengthwise of the car under impact from collision or other cause will be resisted.

The invention consists in the improvements to be more fully described hereinafter, and the novelty of which will be particularly pointed out and distinctly claimed.

I have fully and clearly illustrated my invention in the accompanying drawings to be taken as a part of this specification, and wherein:

Figure 1 is a vertical central section view through a car embodying my invention.

Fig. 2 is an enlarged vertical section view 35 of the bulkhead structure shown in Fig. 1.

Fig. 3 is a section on the line 3—3 of Fig. 1.

Fig. 4 is a section on the line 4—4 of Fig. 3.

40 Fig. 5 is a section on the line 5—5 of Fig. 3.

Fig. 6 is a section on the line 6—6 of Fig. 1.

Fig. 7 is a detail sectional view.

45 Before proceeding with the detailed description of a preferred embodiment of my invention I desire to make it understood that the invention is not limited to any particular structure or type of car, both as regards the design thereof and the material of which it is constructed, as it is applicable to various types of cars whether constructed of wood or of metal, or constructed in part of wood and in part of metal. For the pur-

poses of this application I have shown the 55 invention, and describe it hereinafter, as applicable to a passenger coach constructed of sheet metal of the pressed unit panel side truss type forming the subject-matter of United States Letters Patent No. 909,844, 60 dated January 12, 1909, granted to me.

Referring to drawings by characters of reference, and particularly to Fig. 3, 1 designates generally the underframe structure of a car, which structure may be of any 65 suitable construction, but preferably consisting of longitudinally extending center sills 2, having attached thereto cross-bearers 3 supporting the floor 4, the outer ends of said cross-bearers being connected to the 70 longitudinally extending side sills 5. 6 designates unit panel side truss frames forming part of the sides of the car and the window openings 7, said side truss frames being preferably attached to vertical side 75 posts 8 attached to the side sills 5, and connected to said side sills, the upper ends of said side posts being connected by pressed steel carlines 9 in arch form, all as clearly shown in Figs. 1, 2, 3 and 4 of the drawings. 80 The specific construction of the posts 8 is immaterial, but I prefer that it consist of U-shaped members, the flanges 8^a of which are turned toward each other, as clearly shown in Fig. 2 of the drawings. Extending 85 over the carlines 9 is the roof sheathing 10 completing the roof covering. The end walls of the car are indicated at 11, being riveted to the body corner posts, and 12 designates the platform inclosures or vestibules 90 having the usual ingress and egress doors for the passengers.

I will now proceed to describe the novel construction of the car body end structure embodying my present invention, said body 95 end structure being designed to prevent the body end of the car being crushed inward upon the interior of the car body, and also to prevent spreading of the side walls of the car at the ends thereof, so as to prevent 100 telescoping of the end of another car within the body end of the car body provided with the improved construction. In the preferred embodiment hereinafter described I provide means for tying together the ends 105 of the side walls of the car at the roof line, so as to adequately develop the full shock-resisting capabilities of the side wall mem-

bers adjacent to the roof line, and for this purpose employ means for rigidly connecting the side walls of the car at the roof line and at or near the body end, so as to form a rigid structure adapted to receive and resist impact on the body end of the car due to collision or other cause, and also to so tie the side walls together at the roof line as to prevent spreading of said side walls. Means is also provided for tying together said body end structures at the opposite ends of the car, respectively, so as to prevent movement of the said structures inward lengthwise of the car due to impact, this being preferably accomplished by a longitudinally extending member at the roof line connecting and bracing such structures. I will now proceed to describe in detail a preferred embodiment of my novel car body 20 end structure.

The improved body end structures are each preferably of a double bulkhead type, and may be constituted by the body end wall structure 11 of the car dividing the car body 25 from the platform inclosure and by an intermediate structure, which may be in the form of a transverse partition or wall 13 spaced apart a suitable distance, say approximately six feet from the wall 11, said walls 30 11 and 13 forming, if desired, an accommodation space for any desired purpose. This double structure is preferably constructed with four vertical posts 14, supported at their lower ends by, and secured to, the 35 underframing of the car, two of such posts being at each side of the car. If desired the posts at the extreme ends of the car body may consist of the usual body corner posts 8, heretofore described, and the two 40 intermediate posts may be additional posts, or may be two of the side posts 8, heretofore described. In the preferred construction, these posts form part of the side wall of the car. Lying over the upper ends of these 45 posts is a plate 15, preferably disposed in a horizontal plane, which plate may constitute the ceiling of the accommodation space at the end portion of the car, said plate being connected to the posts by any suitable 50 means, for instance angle irons 16, said angle irons 16 engaging said posts and plate and being riveted thereto. The side edges of the plate 15, which extend longitudinally of the car, preferably overlie the upper horizontal edge portions of the side walls of the 55 car, and are rigidly connected thereto, the said side walls having inwardly extending horizontal flanges 17, to which said side edges of the plate are connected by rivets, 60 whereby said plate constitutes a tie member designed to resist spreading of the side walls in case of collision, so that said side walls will not be separated to permit the end of another car to be telescoped between the 65 same. If desired, the plate 15 may be braced

by two pairs of intermediate columns 18, located at the end wall 11, and the intermediate wall 13, said posts having their lower ends rigidly supported on and connected to the underframing and having their upper ends connected to the said plate by means of angle irons riveted to said columns and plate respectively. These columns 18 may, if desired, serve as door posts to define the passageway or doorway 19 leading through the wall 11 and partition 13, from the platform to the interior of the car body. Extending transversely of the car, at the posts connected by the plate 15, are partition plates 20, riveted to the said corner posts of the end structure, said plates serving as means to brace and stiffen the structure as well as to constitute partitions between the platform and the saloon space, and the car body and the saloon space. The plate 15 is made heavy and rigid enough so as to effectually and rigidly connect the car side walls, and so as not to buckle or crumple under collision impact. The upper portion of the body end structure is closed at its ends by vertical heads or plates 21, riveted to the side faces of the carlines, and also to transverse tie members extending across the car and riveted to the said plate 15. Extending over the carlines and covering the space between the bulkhead walls is a roofing plate 22, which may be the ordinary roofing plate, but which I prefer to make heavier than the ordinary plate, and the side edges of which are connected to the upper side edges of the side walls of the car at the roof line by rivets 22a, as seen in Fig. 3, so that a rigid construction is provided. This reinforcing roof plate not only assists in tying the side walls of the car together, but also resists movement of the end portions of the body end structure toward each other longitudinally of the car. The plates 21, heretofore referred to, resist collapse of this roof sheathing 22 in case of overturning and rolling of the car.

From the above description it will be seen that a body end structure is provided which is extremely rigid in construction, and which is well adapted to resist collapse of the end portion of the car body due to collision impact, and which also lessens the likelihood of telescoping, inasmuch as the side walls adjacent the roof line are tied together in such a manner as not to spread under ordinary collision conditions.

As above stated, my invention also contemplates the tying together and bracing of the body end structures at both ends of the car, so that any tendency of the said structures to move inward lengthwise of the car under impact will be resisted. This is accomplished by providing a girder extending lengthwise of the car at or adjacent the

roof line. This girder may take a number of forms within my invention, but I prefer to employ a structure like or similar to the one disclosed in an application filed under even date herewith 857,660, renewed under S. No. 170,565, and constituting the joint invention of Lewis B. Stillwell and myself.

I will now describe briefly one form of the girder disclosed in said joint application in order that the combination constituting my present invention will be understood, but I desire to have it understood that the other forms of said girder disclosed in said joint application, or girders of other constructions 15 which will serve the purpose, may be employed if desired.

Extending from the upper end of each of the side posts 8 is a connecting plate or gusset 23, riveted at its lower end to a flange 20 of the side post 8, as at 24, and having its upper end riveted, as at 25, to an adjacent carline at a point adjacent the juncture of the side walls of the car with the lower edge portion of the roof sheathing. Running 25 lengthwise of the car and parallel with the side walls of the latter, at a point beneath the carlines, and preferably, although not necessarily, in the same horizontal plane with the line of juncture between the side 30 walls and the roof, are longitudinally extending beams or sills 26, preferably consisting of L-shaped angle irons each having a horizontally disposed flange 27 and a vertically disposed flange 28. These sills 26 35 are preferably connected to the carlines by means of flanged posts or stanchions 29, the lower ends of which posts are riveted to the vertical flanges of the deck sills, as at 30, while the upper ends are riveted to the side 40 flanges of the carlines, as at 31. Connecting the carlines at points adjacent the upper ends of the side posts or stanchions 29 are flanged tie members or stiffeners 32, preferably U-shaped in cross-section (see Fig. 2) 45 and so disposed that one of the side flanges or legs 33 thereof runs parallel with the roof sheathing and is riveted thereto, as at 34. These tie members may be fastened at their ends to the sides of the carlines by means of 50 angle clips 34^a, which are also riveted to the adjacent side faces of the carlines and said tie members, as shown in Fig. 4. The lower horizontal flange 27 of each deck sill is connected preferably to the side wall of the 55 car by means of L-shaped cross-bars or stiffener members 35, the ends of which are riveted respectively to said horizontal flange 27 of the deck sill and to the side faces of the gusset pieces 23, heretofore described, as 60 at 36, 37, respectively.

Extending lengthwise of the car at each side thereof, respectively, are vertical plates 38, the upper horizontal edges of which are riveted, as shown at 39, to the inner flanges 65 40 of the tie members 32, while the lower

edges of said plates 38 are riveted respectively as at 28^a to the vertical flanges 28 of the deck sill 26, said plates 38 being also riveted, as at 41, to the vertical side flanges 29^a of the stanchions or posts 29, see Fig. 3. 70 Running longitudinally of the car on each side of the latter and beneath the cross-pieces 35 is a horizontal plate 42, said plate being riveted, as at 43, to the horizontal flanges 44 of the said cross-pieces 35, see Fig. 5. It 75 will be seen that the structure just described provides a longitudinally extending beam or girder member extending from end to end of the car on each side of the car between the bulkheads and adapted to resist impact 80 on said bulkheads, said beam or girder being in box-girder form and composed of the roof sheathing 10, the plate 38 and the plate 42 with their internal bracing members 29, 35, and the inclosed portions of the carlines, 85 as well as the deck sills 26 and longitudinally extending tie members 32. The upper longitudinal flanges 17 of the side walls serve as longitudinal connecting members 90 for the girder members at the roof line of the car at the upper edges of the side walls, the edges of the plates being riveted to said flanges. As clearly indicated in Figs. 2 and 4 the ends of the horizontal plates 42 abut the innermost transverse edges of the plates 95 15, so that the box-girders will properly resist any inward movement of the bulkhead structure. The plates 15 and 42 preferably abut at a point adjacent the lower edges of the heads or plates 21, at which point one 100 of the stiffeners or cross-pieces 35 is riveted, both to said plate 42 and to the plate 21, as shown at 35^a, 35^b, in Fig. 4 of the drawings. Angle irons or stiffeners 21^a may be provided on the opposite side of the plate or 105 head 21 from the cross-piece 35, and riveted to the said plate 21, and the adjacent edge portion to the plate 15, as shown at 21^b, 21^c. Preferably the edges of the outer roof sheathing 10 are riveted to the flange of the 110 carlines at the bulkhead partition as at 10^a, and also through the heavy roof sheathing plate heretofore described, as at 10^b.

In Fig. 5 I have shown the longitudinally extending deck sills 26 as being rigidly connected to said plate 15, the ends of said sills being carried up over the surface of the said plate, as shown at 45, and each having its horizontally disposed flange riveted thereto, as at 46. Said end of the deck sill may also 120 be connected to the car body end structure by being connected to the vertical plate 38, in which case an angle iron or stiffener 47 may extend lengthwise of said plate 38 at the angle between the same and the plate 125 15, suitable rivets 47^a being passed through the deck sill, the plate 38, and the vertical flange of said angle iron, the horizontal flange of the angle iron being riveted as at 47^b to the plate 15, as shown in Fig. 7. 130

Other means may be provided for effecting this connection, but the one described will prove efficient.

In this construction I preferably construct the vestibule structure of a lighter and more easily collapsible structure than the body end structure, or, in other words, the member 15, preferably does not extend over the vestibule, so that the initial shock resulting from collision impact will be cushioned by the vestibule structure, and the full force of the blow reduced to the point where it will be largely, if not completely, resisted by the car body end structure. I believe I am the first to provide a car body end structure including a heavy impact-resisting member, located at or adjacent the roof line and tying the body side walls rigidly together, in combination with a relatively collapsible vestibule structure adapted to act as a cushion.

I also believe I am the first to produce a car body end structure, in which the side walls of the car are tied together at the roof line by means of a plate or other integral structure for sufficient distance lengthwise of the car to adequately develop the full shock-resisting capabilities of the side wall members adjacent the roof line.

By the term "side wall" as employed in these specifications, I do not limit myself to the particular type of side wall shown and described, but use the term to include side walls of any type or structure and to include the side wall structure as a whole, and not to refer to any particular element or elements which may constitute part of the side wall.

What I claim and desire to secure by Letters Patent of the United States is:

1. A car structure comprising a floor, side walls, end walls, a roof, and a rigid plate connecting the side walls at the end of the car and at a point adjacent the juncture of the roof and the side walls, said plate projecting from an end wall lengthwise of the car within the car body.

2. A car structure comprising a floor, side walls, end walls, a roof, and a horizontally disposed plate connecting the side walls at the end of the car and at a point adjacent the juncture of the roof and the side walls, said plate projecting lengthwise of the car within the car body, and means for bracing said plate at a point between the side walls.

3. A car structure comprising a floor, side walls, end walls, a roof, a horizontally disposed plate connecting the side walls at the end of the car and at a point adjacent the juncture of the roof and the side walls, and means for bracing said plate at a point between the side walls.

4. A car structure comprising a floor, side walls, end walls, a roof, a horizontally disposed plate connecting the side walls at the

end of the car and at a point adjacent the juncture of the roof and the side walls, and columns supporting and bracing said plate at points between the side walls.

5. A car structure comprising a floor, side walls, end walls and a roof, end columns and intermediate columns on opposite sides of the median line of the car, means for connecting said columns to the said side walls, and a rigid member connecting said end columns and intermediate columns to resist spreading of the latter both lengthwise and transversely of the car. 70

6. A car structure comprising a floor, side walls, end walls and a roof, end columns and intermediate columns on opposite sides of the median line of the car, means for connecting said columns to the said side walls, a rigid member connecting said end columns and intermediate columns to resist spreading of the latter both lengthwise and transversely of the car, and means for connecting said rigid member directly to the side walls at the juncture of the latter with the roof. 80

7. A car structure comprising a floor, side walls, end walls and a roof, end columns and intermediate columns on opposite sides of the median line of the car, means for connecting said columns to the said side walls, a rigid member connecting said end columns and intermediate columns to resist spreading of the latter both lengthwise and transversely of the car, and means for connecting said rigid member directly to the side walls at the juncture of the latter with the roof, said end and intermediate columns being spaced apart lengthwise of the car a sufficient distance to develop the impact-resisting capabilities of the side walls. 90

8. A car structure comprising a floor, side walls, end walls, a roof, a plurality of columns at the end of the car on opposite sides of the median line of the latter, and a horizontally disposed plate connecting the upper portions of the columns to resist spreading of the columns lengthwise and transversely of the car. 100

9. A car structure comprising a floor, side walls, end walls, a roof, a plurality of columns at the end of the car on opposite sides of the median line and the latter, and a horizontally disposed plate connecting the upper portions of the columns to resist spreading of the columns lengthwise and transversely of the car, said plate being rigidly attached to the side walls of the car. 110

10. A car structure comprising a floor, side walls, end walls, a roof, end structures for the car each comprising a plate attached to the side walls and adapted to resist spreading of the latter, said plate extending lengthwise within the car body a sufficient distance to develop the impact-resisting capabilities of the side walls, a roof sheet at- 120

tached to the ends of said plate at the side walls of the car, and a girder member extending lengthwise of the car and adapted to resist collapse of said end structures.

5 11. A car structure comprising a floor, side walls, end walls, a roof, a horizontally disposed plate at each end of the car connecting the side walls at a point adjacent the roof line and extending lengthwise of the car a sufficient distance to develop the impact-resisting capabilities of said side walls, and a girder extending longitudinally of the car and connected to and bracing said plates.

15 12. A car structure comprising a floor, side walls, end walls, a roof, horizontally disposed plates connecting the ends of the side walls within the car body, a reinforcing roof sheathing member connecting the side walls and extending over each of said plates, and a girder extending lengthwise of the car and resisting movement of said plates and roof sheathing members lengthwise of the car.

25 13. A car structure comprising a floor, side walls, end walls, a roof and an end structure comprising a horizontally disposed plate connecting the ends of the side walls adjacent the roof structure, and a reinforcing roof sheathing member overlying the said plate and connected to the side walls at points adjacent the ends of the plate.

35 14. A car structure comprising a floor, side walls, end walls, a roof, corner posts for the side walls, and a horizontally disposed plate located at the roof line and attached to said side walls and said corner posts, said plate extending lengthwise of the car a distance sufficient to develop the impact-resisting capabilities of the said side walls.

45 15. A car structure comprising a floor, side walls, end walls, a roof, and a substantially rigid plate connecting the side walls at the end of the car at a point adjacent the juncture of the roof and the side walls, said

plate extending lengthwise of the car a distance sufficient to develop the impact-resisting capabilities of said side walls.

16. In a car structure, a body having side 50 walls, a vestibule structure and a body end structure, said body end structure including a rigid plate uniting the side walls of the car at the roof line within the car body and extending lengthwise of the car a distance sufficient to develop the impact-resisting capabilities of the said side walls, said vestibule structure being constructed to collapse under impact more readily than the body end structure.

60 17. In a car structure a body having side walls, a vestibule structure and a body end structure, said body end structure including a rigid plate uniting the side walls of the car at the roof line and located wholly within the car body and extending lengthwise of the body a distance sufficient to develop the impact-resisting capabilities of the side walls.

65 18. A car structure comprising a floor, 70 side walls, end walls, a roof, and a horizontally disposed plate connecting the side walls at the end of the car and at a point adjacent the juncture of the roof and the side walls, said plate projecting lengthwise of the car within the car body.

75 19. A car structure comprising a floor, side walls, end walls, a roof, and a rigid member connecting the side walls at the end of the car at a point adjacent the juncture 80 of the roof and the side walls, said member extending within the car body a distance sufficient to develop the impact-resisting capabilities of said side walls.

85 In testimony whereof I have hereunto signed my name in the presence of two subscribing witnesses.

FRANCIS M. BRINCKERHOFF.
